UNITED STATES PATENT OFFICE

CHARLES F. STACKPOLE, OF LYNN, MASSACHUSETTS, ASSIGNOR TO THE TURNER TANNING MACHINERY COMPANY, OF PORTLAND, MAINE, A CORPORATION OF MAINE

STAKING MACHINE

Application filed September 9, 1924, Serial No. 736,724. Renewed June 19, 1928.

This invention relates to staking machines and more particularly to staking machines which are provided with a plurality of staking tools for operating on the work.

5 While a number of machines on the market perform staking operations on various kinds of leather with results more or less satisfactory, the staking of glove leather is still performed in this country by skilled 10 workmen called knee-stakers. In knee-staking operations the workman draws a skin back and forth over the edge of a staking blade fastened to the upper end of a post or standard fixed to the staking-room floor, 15 and in these operations his bare knee is employed as well as his hands in holding and in forcing the skin with the requisite tension over the edge of the blade. It will be readily understood that such operations require 20 skilled workmen with strong hands and with the skin of the hands and of the bare knee accustomed to sense the correct tension on the skin under varying conditions and for 25 all portions of the skin undergoing the staking operation. Not only must the worker be skilled in knee-staking operations but he must also be physically strong and of unusual endurance since knee-staking is very 30 laborious and since the operator must stand on one foot the greater part of the time and at all times in a position humped over his work.

In view of the foregoing, it is an object of 35 this invention to provide a machine, especially adapted to the staking of glove leather and of leather having similar qualities for other purposes, by the use of which such staking operations may be performed economically and otherwise satisfactorily and 40 without involving arduous labor on the part of the workmen.

To this end and in accordance with important features of the invention, there are 45 provided in the illustrated embodiment of the invention two staking tools arranged to operate simultaneously upon opposite sides of a piece of leather, one staking tool being movable over and around the operative edge of the other staking tool to bend the work 50 sharply over the edges of both tools to effect

stretching of the leather in substantially equal amounts on its two surfaces. Preferably, and as shown, one staking tool has an inclined operative portion and an operative stroke in a direction away from the direction 55 of inclination of the operative portion of the blade so that there is no tendency of the blade to cut into the work. While the flesh side of the skin is operated upon directly by the sharp staking blade which scrapes and 60 flexes and stretches the same, the grain side is also operated upon indirectly by the same blade, since it is the acute bending of the grain surface over the edge of the blade which effects the opening up of the pores of the 65 grain side and the softening and stretching thereof. In the illustrated construction one staking tool is mounted eccentrically for operative movement with respect to a roller which presses the skin against the other staking tool, the arrangement being such that the first-mentioned tool not only moves over the edge of the second staking tool but inwardly toward the same so as to insure that 70 the skin will be bent over the said edge with the requisite sharpness in the angle formed in the skin. The described eccentric mounting of one of the staking tools also facilitates proper adjustment of the tool with respect to the roller and to the other staking tool. 75 Since the illustrated machine is especially adapted to the staking of skins or other pieces of leather having both a grain and a flesh side, it is important that the staking tool which engages with the grain side in 80 folding the skin over the sharp edged staking tool should not work any injury to the grain surface. Hence, the illustrated grain-contacting staking tool is provided with an operative edge which is considerably more 85 rounded than the operative edge of the other staking tool.

As heretofore constructed, staking machines have been provided with means for 90 adjusting the staking tools to the thickness of the work. In all such cases, however, adjustment for thickness has always been a difficult matter with little likelihood of suiting the staking pressure exactly to the requirements 95 of work varying so much in thickness as does 100

leather. It is an important feature of the present invention that in addition to the adjustment which may be secured through proper manipulation of adjusting devices associated with the staking tools, there is also provided an automatic adjustment of the tension of the staking operation, the staking tools adjusting themselves to a substantial range of variations in the thickness of a skin and yielding to a predetermined maximum resistance, thus eliminating danger of over-stretching the thicker parts of the skin and of tearing the skin where perforations or other defects occur. Furthermore, the illustrated construction comprises improved means for varying the tension, and hence the severity, of the staking operation for skins of different grades which comprises a member arranged for operation by the operator, at any and all times whether the machine be running or not, for controlling the force of the staking operations so that the effect of the operation on the work may be lessened or increased instantly in accordance with the judgment of the operator. In the construction shown this manually controlled means comprises a knee lever having connections for raising or lowering the guideway which controls an eccentric operating to vary the position of the carrier of one of the staking tools with respect to the other.

The invention resides further in a staking machine organization in which the closing movement of the staking tools upon the work takes place much more quickly than in any known prior construction, the purpose being to have the work gripped promptly at the beginning of the operative stroke of the staking tools, thus providing a very efficient mechanism for operating on small skins and on the tabs and various other projecting portions of skins. While operators may adjust themselves to the slower closing of the staking tools in prior constructions, the improved means for securing prompt gripping of the work at the very beginning of the operative stroke of the staking head has the effect of facilitating greatly the work of the operator in staking skins of all sizes, including particularly those having many tabs and great irregularity of outline.

Other features of the invention and novel combinations of parts will be described in the specification and pointed out in the appended claims.

In the drawings

Fig. 1 is a view in side elevation of a staking machine disclosing one embodiment of the invention;

Fig. 2 is a similar view on an enlarged scale showing certain of the parts in section, the table being removed on the near side the better to disclose the operating parts.

Figs. 3, 4 and 5 are views of the staking instrumentalities with certain portions of

their operating means shown in side elevation, a part of the work supporting table being broken away as in Fig. 2;

Fig. 6 is a view on an enlarged scale of the curved staking tool with its mounting;

Fig. 7 is a view looking from the left in Fig. 6 and showing certain of the parts in section;

Fig. 8 is a detail of the guiding slide for the carrier upon which the staking tools are mounted;

Fig. 9 is a detail front view showing the carrier and its relation to the guideways which support and guide the carrier;

Fig. 10 is a plan view from above of the manually operable controlling member by which the tension of the staking operations may be regulated;

Fig. 11 is a detailed view of the lower staking blade or tool, and

Fig. 12 is an edge view of the tool shown in Fig. 11.

In the illustrated machine there is provided a table 14 (Figs. 1 and 3) for supporting the work the table being preferably strengthened by cleats or other reinforcing members 16.

Carried at the front end of the table is a cylindrical member or roll 18 which is normally secured against rotation but is adjustable so that new surfaces can be presented for engagement with the work when other surfaces become worn, the purpose of the roll being to present a curved friction surface against which the work may be pressed by the operator.

Usually the operator wears a pad on the body so that while leaning forwardly the pad is pressed against the work where the latter passes over the roll. Supporting the table 14 is an upper part of a frame 20 which supports also the other parts of the staking machine instrumentalities. As shown, particularly in Fig. 9, the upper part of the frame 20 comprises two members 22 spaced rather widely apart from each other and each provided with a groove 24.

Secured to the top surface of each member 22 is a plate 26, the inner edge of which overhangs the groove 24 whereby a guideway is provided for a longitudinal edge of a carrier 28. It will be understood then that the carrier 28 is supported in the grooves or guideways 24 for longitudinal reciprocation therein by means that will hereinafter be described. Preferably, and as shown, the plates 26 are secured in place by means of bolts 30 which may be loosened to permit of adjustment of the plates through proper manipulation of screws 32, the bolts 30 being again tightened to hold the plates 26 in adjusted position.

For reciprocating the carrier 28 there is provided power means comprising a connecting-rod 40 (Figs. 1 and 2) pivotally connected at one end to a crank 42 which is secured to a shaft 44, the latter being driven by power furnished in any desired or well known manner

as, for instance, by a belt pulley 46 secured to the shaft 44 and arranged to be driven by a belt from a line shaft. At its other end the connecting rod 40 is fixedly mounted on a bar 50 (Figs. 2 to 5 inclusive) which turns in bearings in two downwardly projecting arms 52 fixedly secured to or integral with the carrier 28, the rod or bar 50 being mounted rotatably in the ends of the arms 52. Pivotally mounted 5 on the same bar 50 is a cam member 54 which, in the construction shown, is provided with an elongated slot 58 adapted to receive a bolt 56 secured to the adjacent end of the connecting-rod 40. Upon loosening the bolt 58 the cam member 54 may be adjusted about the center of bar 50 and then secured in adjusted 10 position upon tightening the bolt 58. By this provision for adjustment of the cam member 54 it is possible to secure in connection with other devices which will be hereinafter described the requisite accuracy in the adjustment and operation of the staking instrumentalities.

Secured to the upper surface of the carrier 25 28 is a standard 60 having a forwardly directed arm portion 62 to which is bolted a beam 64 preferably of wood to give a certain amount of yield or flexibility in the beam. Bolted to the forward end of the beam is a 30 yoke member 66 provided with means for carrying a curved staking member or tool 68, the operative edge of which is considerably more rounded than the operative edge of the other staking member hereinafter described.

As shown most clearly in Figs. 6 and 7, the 35 yoke 66 comprises two downwardly extending arms 70 provided at their lower ends with bearings for a shaft 72 having rigidly secured thereto a pressing member or roller 74 having wrapped around its cylindrical surface a felt covering material designed to engage, with a certain amount of friction, the work as the latter passes in engagement with the roll 74, the curved staking member or tool 40 68, and with an inclined staking tool or blade member 69. As shown, the end of the shaft 72 carries a collar 78 rigidly secured thereto and adapted to be yieldingly engaged by a 45 brake member 80 pivoted at 82 and having a curved portion for engaging substantially one half of the cylindrical surface of the collar 78 in a braking action under pressure exerted by a spring 84 which is engaged with an upwardly extending arm 86 of the brake member 80, means being provided, as by an adjustable bolt 90, for varying the tension of the 50 spring 84 in a manner that will be readily understood upon inspection of the drawings and particularly of Fig. 6. The purpose of the 55 brake is to prevent the pressing member or roller 74 from turning too readily, it being especially desirable that a certain definite maximum amount of gripping action on the work should take place while all portions of the 60 skin are being treated. In other words, if the pressing member or roller 74 were free to turn without friction it would make difficult the proper action of the staking tools on the skin, since to effect the staking operation there must be a gripping of the skin between 65 the staking edges of the tools, a resistance to relative movement between the skin and the tools which would be greatly lessened if the roller 74 could spin freely in its bearings. And this lessened grip on the material would be more noticeable as the staking tools reached nearer and nearer to the edge of the skin in a staking operation than it would be while the staking tools were operating upon 70 portions of the skin at a considerable distance from the edge in line of operation.

For moving the curved staking tool 68 into and out of co-operative relation to the other staking tool 69, it is mounted, in the construction shown, in a pair of bell crank levers 94 75 one adjacent to each end of the shaft 72. Preferably and as shown the bell crank levers 94 are not pivoted directly upon the shaft 72, the purpose being to provide an adjustable connection between the curved staking member or 80 tool 68 and its ultimate support, the shaft 72. Pivoted upon boss 98 extending inwardly from the arm 70 is a link 100 which receives 85 rotatably in a bearing at its upper end one end of a shaft 102 the middle portion of which 90 is engaged rotatably by a bearing 104 at the front end of a rod 106 which is reciprocated by means which will hereinafter be described to cause a rocking movement of the staking member or tool 68. As shown, the middle 95 portion of the bell crank lever 94 has an elongated opening 109 to engage loosely over a boss 110 extending laterally from the boss 98, set screws 112, 114 being employed to adjust the bell crank 94 on the boss 110. It will 100 be clear that by means of the bolts 112, 114 the staking member or tool 68 may be adjusted inwardly with respect to the adjacent surface of the roll 74 and also with respect to the second staking tool 69 which will hereinafter be described. Bearings for the ends 105 of the shaft 102 are also provided in the upper ends of the bell cranks 94. For causing the other ends of the bell crank levers 94 to grip and securely hold the curved staking 110 tool 68, a bolt or rod 120 is passed through the free ends of the bell crank levers 94 external to the member or tool 68 so that upon tightening the nuts upon the bolt or rod 120 the opposite ends of the staking tool 68 are 115 securely clamped to hold the tool rigidly in place in grooves on the inside surfaces of the bell crank levers 94. The curved tool 68 is struck about a center eccentric to the center of the shaft 72 so that it is spaced wider, with 120 respect to the roll 74, at its upper edge than at its lower edge to clear any waste material that might get in between the tool and the roll. As before stated the rod 106 is reciprocated to cause rocking movements of the 125 tool 68.

curved staking tool 68 and for this purpose the other end of the rod 106 is pivotally connected to the upper end of a lever 122 (Figs. 2 to 5 inclusive), the other end of which is rigidly connected to a short shaft 124 supported by spaced projections 126 (Figs. 2 and 5) from the lower surface of the carrier 28, the shaft 124 being rotatable in its bearings. Secured to the shaft 124 is a second lever 128 having a roll 130 for engagement with portions of the cam member 54, a spring such as a leaf spring 132 being employed for holding the roll 130 constantly in contact with cam surfaces on the cam member 54. If desired a coiled spring 133 (Fig. 2) may be employed to supplement spring 132, since spring 133 can be more readily adjusted as to tension. When the cam member 54 is operated to cause the high point 134 thereof to engage with the roll 130 the rod 106 is moved to the left in Figs. 3, 4 and 5 and held for a time at the extreme limit of its movement in this direction so that the curved staking tool 68 is maintained in operative position during the working stroke of the staking tools 68 and 69. Preferably, and as shown, the rod 106 has interposed at a point intermediate between its ends a yielding portion or member indicated in general by the reference character 140 (Figs. 3, 4 and 5). Upon reference to Fig. 2 of the drawings it will be seen that this yielding connection 140 comprises a casing 142 (Fig. 2) which is conveniently screwed upon a cap 144 screw-threaded on the rod portion 146. At its other end the casing 142 has a head portion which is perforated to receive the adjacent end 148 of the rod 106, the end of the rod carrying a piston member 150, a spring 152 being interposed between the piston 150 and the cap 144 and under tension normally to maintain the piston 150 in contact with the adjacent end of the casing 142. It will be readily understood upon inspection of the drawings that compression of the spring 152 will permit yielding of the curved staking tool 68 in a direction away from the adjacent surfaces of the roll 74 and of the lower staking tool 69 hereinafter to be described. The spring connection just described makes provision for considerable self-adjustment of the staking tools to variations in the thickness of the skins being operated upon, and particularly variations in thickness of different parts of the same skin, and provides for a nice adjustment of the pressure of the staking operation such as cannot be secured even by accurate adjustments of the staking tools themselves. There is thus provided a safety device to prevent tearing of the work or excessive strain or harshness of treatment.

For co-operation with the upper curved staking tool 68 there is provided, as already stated, a second staking tool 69 shown in detail in Fig. 11. This staking blade 69 has a curved operating edge considerably

sharper (Fig. 12) than the corresponding edge of the staking tool 68 and yet not so sharp as to operate as a cutter but rather as a tool which will insure a very abrupt bending of the portions of the skin as they pass over this edge. In other words, the blade will operate as a scraper on the skin and have the effect of softening the material through the bending and stretching of the fibres of the skin, it being understood that this blade operates directly upon the flesh side of the skin while the upper curved staking tool 68 is in engagement with the grain side of the skin to bend the skin sharply over the blade. Conveniently the blade 69 is mounted securely upon an angle iron 160 (Fig. 2) being preferably bolted thereto as by bolts 162. Preferably, and as shown, the angle iron 160 is adjustably connected to the forward end of a lever 164 by means of a second angle iron 166 which is securely bolted to the front end of the lever 164 and which provides a substantially vertical attaching face for the angle iron 160. Upon loosening bolts 168 the angle iron 160 can be adjusted vertically through proper manipulation of set screws or setting bolts 170 after which the bolts 168 may be again tightened to hold the angle iron 160 in adjusted position. As will be clearly understood from an inspection of the drawings accuracy in the position of the staking tool 69 may also be secured by adjustment upon the angle iron 160 prior to tightening of the bolts 162.

Power means is provided for moving the staking tool 69 toward and from the staking tool 68 so that the skin undergoing operation may be operated upon and then released to permit of shifting of the skin between successive staking operations, the said power means in the construction shown comprising the cam 54 already mentioned which has a cam portion 180 for engagement with a roll 182 on the lever arm 184 of the lever 164 which turns pivotally on a shaft 186. For holding the roll 182 in contact with the cam member 54 there is provided a spring 185 which presses against the lever 164. It will be clearly understood that when the roll 182 is engaged with the high part of the cam 180 the staking tool 69 is in full working co-operation with the staking tool 68 at which time the roll 130 is held stationary on the high part of the cam 134, as before described (see Fig. 5 of the drawings).

Since skins for glove leather and for other purposes vary considerably in thickness and in density so that it is quite common to grade even these relatively thin skins into a number of grades, it is desirable to provide means under the control of the operator for adjusting the force of tension of the staking operation to suit the thickness or density grade of skins being operated upon, in addition to the automatic adjustment or accommodation

provided by the spring connection 140. For this purpose applicant has provided a novel construction by which the staking blade 69 may be adjusted relatively to the roll 74, bringing it closer to the roll while thinner skins are being operated upon. This mechanism comprises a member 190 which constitutes a guide member extending longitudinally of the machine, that is, from front to rear in parallelism with the path of movement of the carrier 28. It is to be understood that this guide member is movable only in a vertical plane so that the roll 192 travels along the groove in the guide member 190 during reciprocation of the carrier 28. This roll 192 is at the end of a short lever 194 on the other end of which is an eccentric 196 securely attached to the lever or integrally formed therewith. Upon rocking the lever 194 the eccentric 196 is shifted to raise or lower the fulcrum point of the lever 194 whereby the lower staking blade 69 is adjusted. For raising and lowering the guide member 190 there is provided a manually controllable member having connections with the guide member 190 whereby the latter is maintained always in a horizontal plane during its movements of adjustments. In the construction shown this manually controllable means comprises a segmental wheel 200 (Figs. 2 and 10) which carries members 202 which may serve as handles or as members to be engaged by the knee of the operator, the segmental member 200 being connected by spokes 204 to a vertical shaft 206. Preferably, and as shown, the hub 208 has its upper surface provided with a cam 210 which co-operates with a complementary cam surface 212 which faces downwardly on the lower surface of a fixed block 214 carried by a standard 216 fixed to the frame of the machine. Upon rotating the shaft 206 in the direction of the arrow in Fig. 10, the co-operation of the cam surfaces 210 and 212 results in forcing the shaft 206 in a downward direction whereby the lever 218 is rotated about its pivot 220 by reason of the engagement of the shaft 206 at its lower end with the arm 222 of the said lever. At its other end the lever 218 is connected by a link 224 with a projection 226 securely fastened to or integral with the guide member 190 so that upon depressing the arm 222 of the lever 218 the forward end of the guide member 190 is lifted. In order that both ends of the guide member 190 may be lifted at the same time and in equal amounts there is provided a pair of bell crank levers 228, 230, duplicates of each other in size and shape and pivoted at 232 and 234, respectively, on the frame of the machine. Lever 228 is pivotally connected to the pivot pin 236 which serves as the connection also of the link 224 to the projection 226. Similarly the lever 230 is pivotally connected to the projection 238 which is integral with or securely attached to the guide member 190 adjacent to the rear end thereof. Since the bell crank levers 228, 230 are connected by a link 240 they are constrained to move together and in equal amounts thus insuring that the guide member 190 will be maintained in parallelism with the guideway for the carrier 28 while it is being lifted or lowered.

At the forward end of the groove or guideway 24 for the carrier 28 there is provided a plate 250 (Figs. 8 and 9) which is secured to the frame member 22 by means of a dowel pin 252 and a screw 254, there being one of the blocks 250 in each guideway 24, the purpose of the blocks being to provide stops which would limit the forward movement of the carrier 28 in case of accidental overthrow of the carrier 28, so that no injury to the operator could take place under any conceivable circumstances due, for instance, to breakage or disconnection of the operating parts for the carrier.

In operating with this machine a skin is placed in extended condition upon the table 14 and moved rearwardly as the carrier 28 moves rearwardly, the skin being held by the hands of the operator on each side of the relatively wide slot between the frame members 22. When the skin has been moved far enough into the machine in the judgment of the operator it is held in position against the pull of the staking tools by the body of the operator pressing the skin against the cylindrical member or roll 18. At the rear end of the stroke of the carrier 28 the staking tools 68 and 69 are opened widely apart (as shown in Fig. 3), and upon forward movement of the carrier these tools remain in spread apart condition so that they may be closed upon the skin at substantially the extreme limit of the forward movement of the carrier. These movements of the carrier and of the staking tools are illustrated in Figs. 3, 4 and 5 of the drawings, wherein the carrier with the staking tools in spaced relation is seen in Fig. 3 with the carrier a little to the rear of the middle point of the path of its rectilinear travel. In Fig. 4 the carrier has nearly reached its limit of forward movement and the staking tools are moving toward each other, and in Fig. 5 this closing or gripping movement of the tools with respect to the skin is completed, the closing and opening movements of the staking tools being caused by rocking movements of the cam 54. At the instant that the staking tools close upon the skin the carrier 28 is started on its backward trip, whereby both surfaces of the skin are operated upon simultaneously by the staking tools throughout a stroke which carries the tools nearly the full length of the table 14 from the position shown in Fig. 5 to the end of the table at 260, at which point the staking tools separate to release the skin and to return in spaced relation to each other to grip the skin

in another place as it is shifted by the operator. Upon inspection of Fig. 5 it will be observed that the skin S is bent sharply around the edge of the staking tool 69, just as the skin is bent over the blade in knee-staking, through co-operation of the curved staking tool 68 and the roller 74, and it will be further observed that the staking blade 69 is at such an angle that, during its operative stroke, the skin continues to be drawn over its edge at the same acute angle, the movement of the staking blade being in such a direction however, relatively to the bent portion of the skin that no cutting or tearing of the skin takes place. The flesh side of the skin is stretched and scraped and flexed so as to soften and enlarge the area of the skin. This takes place under yielding tension, as provided for in the construction of the machine by the flexibility of the beam 64 and by the yielding features of the connection 140 in the rod 106. At the same time that the staking tool 69 is operating on the flesh side of the skin S the curved staking blade 68 is contacting with the grain side to assist in stretching this side, between the holding member or roll 18 and the constantly changing point of grip of the staking tools, to substantially the same extent that the flesh side is stretched. Since the grain side is on the outside of the bend in the skin over the blade 69, it is stretched fully as much as the flesh side which receives harsher treatment since it is in contact with the sharp blade. While it is true that the flesh side is operated upon by the blade 69 which gives it a severe stretching and scraping it is to be remembered that the flesh side of the skin is more resistant to stretching than is the grain side so that it needs this harsher treatment. The angular relationship of the two staking tools and the staking edge of these tools have been so constructed and adjusted that substantially the same amount of stretching is secured upon the grain and flesh sides, thus providing for the most desirable results in that there is no tendency to separate the grain side from the flesh side through greater stretching of one as compared to the other. The grain side bent over the sharp blade 69 is thoroughly softened and stretched, and has its pores opened, without contact with the tool that does it, thus avoiding damage thereto. Through the fine adjustments provided for the staking tools, and the control of the tensioning of the tools both automatically and manually through the knee lever 200, 204, there is provided means for staking light skins which enables the machine operators to do more and better work than can be done by knee-stakers. At the same time the operation of the machine involves so little effort that the laborious work heretofore incident to the staking of light skins is substantially eliminated. Applicant believes himself to be the first to

provide a machine adapted to accomplish this work.

Having described my invention, what I claim as new and desire to secure by Letters Patent is:—

1. In a machine of the character described, a staking member for operating on the flesh side of a skin, a roller for co-operation with the staking member, and a member for engaging with the grain side of the skin and movable relatively to the roller and to the staking member for bending the skin sharply over, around, and under the edge of the staking member. 70
2. In a machine of the character described, a staking blade having an inclined operative portion, an operative stroke in a direction opposite to the direction of the inclination of said operative portion, a roller for co-operation with the blade, and a member movable with respect to the blade for folding the work down over the edge of the blade. 80
3. In a machine of the character described, a blade for operating on the flesh side of a skin, a roller for pressing the skin against the blade and a staking member spaced with respect to one side of the blade when the member and blade are in work-receiving position and movable about the axis of the roller to carry its operative edge over the edge of the staking blade and inwardly toward the other side of the blade to bend the skin sharply over the edge thereof. 90
4. In a machine of the character described, a staking blade having a relatively sharp edge for operating on the flesh side of a skin, a roller for holding the skin against the blade, and a staking member having a rounded edge for engagement with the grain side of the skin and having a movement relative to the roller to carry its operative edge over and around the edge of the staking blade so that the skin is bent over edges of both the member and blade whereby both sides of the skin are simultaneously stretched 105
5. In a machine of the character described, a staking blade for operating on the flesh side of a skin, a member for pressing the skin against the staking blade, and a member movable relatively to the pressing member for engaging with the grain side of the skin for bending it sharply over the edge of the staking blade. 115
6. In a machine of the character described, a staking blade having an inclined operative portion and an operative stroke in a direction opposite to the direction of the inclination of said operative portion, a member for co-operating with the blade in stretching the work, and a member movable with respect to the blade for folding the work sharply over the edge thereof. 120
7. In a machine of the character described, a member for operating on the flesh side of 130

5 a skin, a member for pressing the skin against the first-mentioned member in cooperation therewith for stretching the skin, and a staking member movable in a curved path about the pressing member and toward and over the edge of the first-mentioned member to bend the skin sharply thereover.

10 8. In a machine of the character described, a staking blade having a relatively sharp edge for operating on the flesh side of a skin, a roller for holding the skin against the blade, and a staking member having an edge more rounded than the edge of the blade for engagement with the grain side of the skin, and 15 having a pivotal mounting eccentric to the axis of said roller so that operative movement thereof about said pivotal mounting carries its rounded edge down over and in toward the edge of the staking blade whereby the skin 20 is bent sharply over the edge of the staking blade.

25 9. In a machine of the character described, a roller having a friction surface for contact with the grain side of a skin, a staking blade for operating upon the flesh side of the skin, and a member mounted to turn with respect to the roller during each cycle of the machine for bending the skin sharply over the operative edge of the staking blade.

30 10. In a machine of the character described, a roller having a friction surface for engagement with a skin, a staking blade for engaging another surface of the skin, a brake for the roller so as to secure resistance to 35 the passage of the skin over the surfaces of the roller and the staking blade, a member movable for folding the skin over the edge of the blade, a supporting member upon which the folding member is mounted, and 40 means independent of the supporting member for tensioning the holding member so that the latter may yield automatically to variations in the thickness of the work and to other excessive resistances such as may be 45 caused by perforations in the work.

50 11. In a machine of the character described, a roller having a felt-covered friction surface for contact with the grain side of a skin, a staking blade for operating upon the flesh side of the skin, a member having 55 a pivotal mounting eccentric with respect to the center of the roller and operative during movement about the pivotal mounting for bending the skin sharply over the operative edge of the staking blade, and means for adjusting the eccentric mounting to vary the position of the member with respect to the roller and the blade.

60 12. In a machine of the character described, a roller having a friction surface for engagement with a skin, a staking blade for engaging another surface of the skin, a brake for the roller so as to secure resistance to the passage of the skin over the engaged 65 surfaces of the roller and the staking blade,

a member movable for folding the skin over the edge of the blade, a support for the folding member, and means for moving the member, said moving means having a tensioned portion adapted to yield so as to secure automatic adjustment of the folding member to variations in the thickness of the work and to other excessive resistances such as may be caused by perforations in the work.

70 13. In a machine of the character described, a staking tool having an inclined operative portion and an operative stroke in a direction opposite to the direction of the inclination of said operative portion, a rounded-edge staking tool movable to fold a skin over the inclined operative edge of the first-mentioned tool, means for moving the tools toward and from each other to engage with and to release the skin, and means providing for automatic adjustment of the tools with respect to each other.

75 14. In a machine of the character described, a staking tool for operating on the flesh side of a skin, a staking tool mounted to move downwardly and inwardly toward the first-mentioned staking tool so that the skin is folded sharply over the edge thereof, means for moving the tools longitudinally of the skin for stretching and softening the portion of the skin in the path of the tools, said 80 means comprising an arm having a bearing directly over and closely adjacent to the first-mentioned staking tool for pivotally supporting the second staking tool, and means for moving both the tools toward each other 85 one of them about its pivotal support, to grip the work promptly at the beginning of the operative stroke of the tools.

90 15. In a machine of the character described, a staking blade for engaging with the flesh side of a skin, a roller for pressing the skin against the blade, means for adjusting the blade toward and from the roller, a staking member for engaging with the grain side of the skin, means for mounting the 95 staking member for movement toward and from the staking blade, means for adjusting the staking member toward and from the staking blade, and means independent of the mounting means for the staking member for 100 securing automatic adjustment of the staking member with respect to the staking blade 105 during the staking operation.

110 16. In a machine of the character described, a member against which a skin may be pressed by the operator to hold it stationary during a single staking operation, a staking blade for operating on the flesh side of the skin, a staking member mounted to move simultaneously downwardly and inwardly toward 115 and under the staking blade so that the skin is folded sharply over the edges of both the staking blade and staking member during the operative stroke thereof, and means for moving the blade and staking member longi- 120 125 130

tudinally of the skin for stretching and staking both the grain and flesh sides of the portion of the skin in the path of the staking member and blade.

5 17. In a machine of the character described, a pair of staking tools for engagement with opposite sides of a skin, a roller for co-operation with the staking tools, one of the staking tools being oscillatable about the roller, 10 means for moving the oscillatable staking tool over and around the operative edge of the other staking tool whereby the skin is folded sharply over the operative edges of both staking tools, and a carrier for the staking 15 tools reciprocable to move the tools lengthwise of the skin while the latter is held stationary, said carrier comprising means for moving said other staking tool bodily toward the oscillatable staking tool to facilitate 20 gripping of the skin at the very beginning of the operative stroke of the tools.

18. In a machine of the character described, staking tools for engaging opposite sides of a skin, a roller for co-operating with the 25 tools, means for moving both of the tools toward and from the roller and toward and from each other to grip and to release the skin, and a carrier for moving the tools longitudinally of the skin while the latter 30 is held stationary.

19. In a machine of the character described, a pair of staking tools for engagement with opposite sides of a skin, means for moving one 35 of the staking tools over and around the operative edge of the other staking tool whereby the skin is folded sharply over said operative edge, a carrier for the staking tools reciprocable to move the tools lengthwise of the skin while the latter is held stationary, 40 said carrier comprising a resilient arm for supporting one of the staking tools, and means for causing the tools alternately to grip and to release the skin, said means comprising a tension member so that the tools 45 may adjust themselves automatically to the skin undergoing operation.

20. In a machine of the character described, staking tools for engaging opposite sides of the skin, means for causing the tools to grip 50 and to release the skin, a carrier for moving the tools longitudinally of the skin while the latter is held stationary, a yielding device in the said means for permitting automatic adjustment of the tools with respect 55 to each other during their operative stroke, and means under the control of the operator for varying the tension of the staking operation at any time during the staking operation.

21. In a machine of the character described, 60 a staking tool for operating on one side of a piece of work, a staking tool for engaging simultaneously with the other side of the work, means for moving the tools toward and from each other to grip and to release 65 the work, a carrier for the upper tool com-

prising a resilient member designed to permit a relatively small amount of yielding of the tools away from each other should excessive resistance be encountered, said means for moving the tools toward and from each other comprising a yielding device whereby the tools may adjust themselves automatically to variations in the thickness of the work and to the resistance offered by the work, and means under the control of the operator for varying the staking pressure at any time in accordance with the judgment of the operator.

22. In a machine of the character described, staking tools for operating on opposite sides 80 of a piece of work, a carrier for the tools, means mounted on the carrier for causing the tools to grip and to release the work, said means comprising a lever for moving one of the tools toward and from the other, said lever being provided with an eccentric mounting, a member connected to the eccentric mounting and having a roll at its free end, a guideway in which the roll travels during reciprocation of the carrier, and means 85 under the control of the operator for raising or lowering the guideway, thereby adjusting the eccentric mounting and varying the position of the tools with respect to each other whereby the tension of the staking operation may be varied at the will of the operator.

23. In a machine of the character described, staking tools for engaging opposite sides of a piece of work, a carrier reciprocable to 100 move the tools lengthwise of the work while the latter is held stationary, means for moving the tools toward and from each other to grip and to release the work, said means comprising a cam having two cam surfaces 105 thereon, levers, one for each staking tool, arranged to be operated by the cam surfaces on the cam member, a yielding connection between one lever and the staking tool operated thereby for varying automatically the 110 tension of the staking operation, and means under the control of the operator for varying the fulcrum point of the other lever to change the relative position of the tools with respect to each other whereby the tension of the 115 staking operation may be changed at the will of the operator at any time during the staking operation.

24. In a machine of the character described, a staking blade for engaging with the flesh side of a skin, a staking member for engaging with the grain side of the skin, means for effecting relative movement of the staking member and the staking blade toward and from each other, means for relatively adjusting the staking member and the staking blade toward and from each other, a supporting member for staking the member, and means for independent of the supporting member effecting automatic relative adjustment of the 120 125 130

staking member and the staking blade during the staking operation.

25. In a machine of the character described, a staking tool for engagement with the flesh side of a skin, a member for pressing the skin 5 against the tool, a second staking tool movable toward the first-mentioned staking tool for folding the skin sharply over the operative edge thereof, means for moving the tools toward and from each other to engage 10 with and to release the skin, and a compression spring providing for automatic adjustment of the tools with respect to each other during a staking operation on the skin.

26. In a machine of the character described, 15 a pair of staking tools for engagement with opposite sides of a skin, a roller for engaging with the skin to retard its movement with respect to the staking tools, and means comprising a spring providing for automatic adjustment of the tools with respect to each other during a staking operation on the skin.

27. In a machine of the character described, a pair of staking tools for engagement with 25 opposite sides of a skin, means for moving one of the staking tools over and around the operative edge of the other staking tool whereby the skin is folded sharply over said operative edge, a roller for pressing the skin 30 against one of the tools, and means for causing relative movement of the staking tools in directions toward and from each other to engage and to release the skin, said means comprising a yielding connection so that the 35 tools may adjust themselves to variations in the thickness of the skin.

28. In a machine of the character described, a staking blade having an inclined relatively sharp edge portion for operating on the flesh 40 side of a skin and having an operative stroke in a direction opposite to the direction of the inclination of the sharp edge portion, a member for holding the skin against the blade, and a staking member having an edge more 45 rounded than the edge of the blade for engagement with the grain side of the skin in bending the latter over the sharp edge of the staking blade.

29. In a machine for staking skins and 50 other light pieces of leather, a staking blade having a relatively sharp edge for operating on the flesh side of a piece of leather, a member for holding the piece of leather against the blade, and a staking member having an 55 edge considerably more rounded than the edge of the blade for engagement with the grain side of a piece of leather for operating thereon in bending the leather over the sharp edge of the staking blade.

30. In a machine for staking skins and 60 other light pieces of leather, a staking blade having a relatively sharp edge for operating on the flesh side of a piece of leather, a member for holding the piece of leather against 65 the blade, a staking member having an edge

considerably more rounded than the edge of the blade for engagement with the grain side of a piece of leather for operating thereon in bending the leather over the sharp edge of the staking blade, and a resilient supporting 70 member for the staking member so constructed that the latter may adjust itself automatically to the piece of leather undergoing operation.

In testimony whereof I have signed my 75 name to this specification.

CHARLES F. STACKPOLE.

CERTIFICATE OF CORRECTION.

Patent No. 1,744,420.

Granted January 21, 1930, to

CHARLES F. STACKPOLE.

It is hereby certified that error appears in the printed specification of the above numbered patent requiring correction as follows: Page 8, line 128, claim 24, for the words "for staking the member" read for the staking member; line 129, same claim, strike out the word "for" and insert the same before the word "effecting" in line 130; and that the said Letters Patent should be read with these corrections therein that the same may conform to the record of the case in the Patent Office.

Signed and sealed this 9th day of December, A. D. 1930.

(Seal)

M. J. Moore,
Acting Commissioner of Patents.
